UNITED STATES PATENT OFFICE.

JOHN N. RHOADS, OF PHILADELPHIA, PENNSYLVANIA, ASSIGNOR OF ONE-HALF TO JOHN M. KEATING, OF SAME PLACE.

BOTTLE-STOPPER.

SPECIFICATION forming part of Letters Patent No. 425,550, dated April 15, 1890.

Application filed June 21, 1889. Serial No. 315,031. (No model.)

To all whom it may concern:

Be it known that I, JOHN N. RHOADS, a citizen of the United States, residing at the city and county of Philadelphia, and State of Pennsylvania, have invented certain new and useful Improvements in Bottle-Stoppers, of which the following is a full, clear, and exact description, reference being had to the accompanying drawings, of which—

10 Figure 1 is a perspective view of the device in use. Fig. 2 is a longitudinal vertical section thereof, the cork and containing-vessel being shown in dotted outline.

15 The nature of this invention is a holder of novel construction for bottle and other stoppers; and it consists of a pivoted spring-controlled thumb-lever attached or adapted to be attached to a bottle or other containing-vessel, and provided with means for holding 20 a stopper in such position relative to the bottle, &c., that the stopper will normally be forced into the mouth of the latter, yet may be readily withdrawn by depressing the outer arm of said lever.

25 The invention consists also in details of construction, which will be hereinafter fully described and duly claimed.

Referring to the annexed drawings, A represents the containing-vessel, which may be 30 a can, bottle, or the like. B represents the stopper, being an ordinary cork in the present instance, and C represents the stopper-holder. This holder in its simplest form is constructed as follows: c' is a yoke whose 35 limbs are designed to embrace the neck of the vessel and to be detachably secured thereto by means of a thumb-screw c² or other suitable device. Projecting from this yoke is an arm c³, which is provided with vertical lugs 40 c⁴, between and in which is pivoted a thumb-lever c⁵, whose forward arm c⁶ is provided with a ring or band c⁷, which is adapted to encircle and support a cork B or other stopper, an arm c⁸, which is pivoted at x on the lever, resting 45 upon and holding the cork.

Secured to the under side of the arm c⁹ of lever c⁵ and bearing against the projecting arm c⁸ is a spring c¹⁰, preferably flat, which normally raises the lever-arm c⁹, and thus 50 presses the cork into the mouth of the vessel, as clearly shown.

It will be seen that by depressing the arm c⁹ of the lever (arrow 1) the cork will be raised from the mouth of the bottle (arrow 2) to permit the outpouring of the liquid, &c., therein 55 contained, the amount of pressure upon said arm determining the extent of elevation of the cork, and of course the outflow of the contents. By swinging the pivoted arm c⁸ away from the cork (arrow 3) the latter may be 60 raised (arrow 4) or lowered by hand, as circumstances may require, or may be entirely removed and reinserted when required.

Instead of the cork being detachably held within the ring by the arm c⁸, the cork may 65 be held therein by friction or by means of a set-screw working in the side of the ring, so as to bear against the cork.

Having thus described my invention, I claim as new and wish to secure by Letters 70 Patent—

1. In a bottle-stopping device, the combination of the pivoted spring-controlled thumb-lever having the open ring c⁷, encircling and holding an ordinary cork, whereby said cork 75 may be withdrawn from the bottle by the act of depressing said lever, and whereby the cork may be wholly or partly withdrawn from the ring and bottle independent of the lever movement, substantially as described. 80

2. In a bottle-stopping device, the combination of the pivoted spring-controlled thumb-lever having the ring c⁷, holding an ordinary cork, and the laterally-swinging retaining-arm carried by the lever and bearing upon the top 85 of the cork, substantially as described.

3. In a bottle-stopping device, the combination of the outwardly-extending arm c⁹, its yoke c', the screw connecting the limbs of said yoke, the horizontal thumb-lever pivoted to 90 said arm and provided with the ring holding an ordinary cork, together with the spring interposed between said lever and arm c⁹, substantially as described.

In testimony whereof I have hereunto affixed 95 my signature this 13th day of April, A. D. 1889.

JOHN N. RHOADS.

Witnesses:
